HEEL BUILDING MACHINE

William Roderick Barclay, Reginald Boyd Woodcock, and Wilfrid Thomas Minett, Leicester, England, assignors to United Shoe Machinery Corporation, Paterson, N. J., a corporation of New Jersey

Application February 21, 1934, Serial No. 712,302
In Great Britain March 29, 1933

11 Claims. (CL. 12—50)

This invention relates to heel building machines and is particularly applicable to machines of the type in which there is a mold in which lifts are assembled, by hand or otherwise, pressed firmly, and secured together to produce a heel. 5

It is an object of the invention to improve such machines with a view to increasing their accuracy and productiveness, facilitating the work of the operator, and safeguarding both 10 the machine and the operator against injury. 10

It is usual in machines of this type to apply pressure to the lifts by means of a presser pad which forces the lift assembly down into the mold and holds it there while nails are driven 15 upward from a nail block, constituting the bottom of the mold, to secure the lifts together, and the heel often becomes stuck so tightly in the mold that it is difficult to remove it. 15

One feature of the present invention consists 20 in the provision of means for lifting the nail block in the mold to eject a heel and, advantageously in addition, to present the block in a convenient position to receive the nails for the next heel. In the illustrative embodiment of the 25 invention shown in the accompanying drawings connections are provided between the presser pad and the nail block whereby the lifting of the nail block is controlled by movement of the presser pad away from the mold, the nail block 30 first being lifted a short distance to free the stuck heel from the mold and then being lifted further to eject the heel. Preferably, and as a 35 part of the invention, additional means, herein illustrated as manually operable, is provided for dropping the nail block back to the bottom of the mold after a fresh load of nails has been inserted in it. 35

Another feature of the invention, aiding in 40 the production of perfect heels, resides in means, additional to the usual power mechanism for operating the nail drivers, for advancing the drivers independently of the power mechanism to permit inspection of the nails with 45 which the nail block has been loaded, in order that the operator may readily determine with certainty that the correct number of nails will be driven in the proper positions. 45

In ordinary use of heel building machines it 50 is frequently necessary to change molds for others of different sizes or shapes and still further features of the invention relate to improvements facilitating the accurate positioning of the mold and preventing the application 55 of power to the presser pad while the molds are being changed. 55

These and other features and advantages of 60 the invention will be better understood and appreciated from reading the following detailed description of one embodiment thereof in con-

nection with the accompanying drawings, in which

Fig. 1 is a front elevation of a machine embodying the invention;

Fig. 2 is a right hand side elevation of the 5 said machine;

Fig. 3 is a section on the line 3—3 in Fig. 2;

Fig. 4 is an elevation partly in section of part 10 of the machine upon a larger scale than that of Figs. 1 to 3;

Fig. 5 is a plan view, partly in section, of some 15 of the mechanism shown in Fig. 4 and upon the same scale;

Fig. 6 is a left hand side elevation of some of 20 the mechanism shown in Figs. 4 and 5; 15

Fig. 7 is a plan view of a detail of a safety 25 mechanism shown in Fig. 2; and

Fig. 8 is a side elevation of the detail shown 30 in Fig. 7.

The illustrative heel building machine, which 35 will be described as being viewed from the front or operator's standpoint, comprises a substantially rectangular frame 2 which has rotatably mounted in its upper portion a horizontal driving shaft 4 extending forwardly and rearwardly 40 of the machine. The driving shaft, at its rear end, has rotatably mounted on it a driving pulley 6 which may be coupled to the driving shaft 4 by means of a single revolution, non-repeating clutch of known construction. Secured to the upper surface of the machine frame, 45 near the front thereof, is an upwardly projecting post 8. The post 8 has in its upper end a cylindrical nail block 10, Fig. 4, which rests on a shoulder 12 formed in a vertical bore in the post 50 8 and has formed in it a number of vertical holes the number and relative spacing of which depend upon the size of the heel to be built and the number of nails which it is desired to drive into the lifts. The nail block 10 has depending 55 from it a stem 14 on which is slidably mounted a plate 16 which supports the lower ends of nail drivers 18 extending upwardly into the vertical holes in the nail block 10. The plate 16 has 60 extending downward from it a short tubular portion 20 surrounding the stem 14 which stem extends below the said tubular portion 20. The tubular portion 20 has formed in the front of it 65 a notch which is engaged by a latch 22 slidably mounted in a vertical plunger 24 which is mounted to slide in the said post 8. The upper end of the plunger 24 supports the said plate 16 the tubular portion 20 of which plate is received 70 in a bore in the plunger. The latch 22 is held 75 in engagement with the notch in the tubular portion 20 by a spring 26 which engages a hand lever 28 pivoted on the plunger 24 and engaging a pin 30 on the latch 22. The stem 14 has 80 at its lower end a head 15 arranged to engage the lower end of the tubular portion 20 on the 85 90 95 100 105 110 115 120 125 130 135 140 145 150 155 160 165 170 175 180 185 190 195 plate 16. When the latch 22 is released by means of the hand-lever 28 from the tubular portion 20, the nail block 10, plate 16 and drivers 18 may be lifted bodily out of the post 8 and a different set of these parts inserted in the post when a change in the size of heel to be built is made and, consequently, a change in the nailing is required.

10 The plunger 24 at its lower end carries a cam roll 32, Fig. 2, rotatably mounted on a pin 34 secured in the plunger and extending forwardly and rearwardly of the machine. The cam roll 32 rests on a cam 36 secured to the driving shaft 4 and the cam is so shaped that a uniform rate of upward movement is given 15 to the plate and drivers during the nail driving.

20 On the top face of the post 8 is secured a plate 38, Fig. 4, which has formed in it an opening of a shape and size to receive the upper end of the nail block 10 which upper end is of a shape and size substantially conforming to the size of the lowest lift in a heel mold hereinafter referred to and enters the opening in the plate 38 so that the upper face of the nail block 10 is level with the upper face of the plate 38 when the nail block is resting on the shoulder 12 in the bore of the post 8.

25 The plate 38 is secured to the post 8 by pins projecting from the upper face of the post which enter holes in the plate so that the plate may be readily removed. Secured to the upper face of the plate and to the post by screws passing through the plate is a mold 40. The mold 40 is in the form of a block having passing through it from top to bottom an opening of a shape 30 and size according to the shape of the heel to be built. The lowermost lift placed in the mold rests on the upper face of the nail block 10 and, it may be, partly on the upper face of the plate 38 on the post.

35 The opening through the mold is usually smaller at its lower end than at its upper end, the walls being relatively inclined according to the shape of the heel to be built, and the lifts are placed in the mold by the operator in proper order i. e., the lifts gradually increase in size from the bottom lift in the mold to the top lift in the mold. To enable the operator, after assembling the lifts in a pile, to conveniently place the pile in the mold the mold may have in its rear wall a narrow gap extending downward from the top of the mold. The lifts are pressed down into the mold and held under pressure during the nailing by a presser pad 42 which is secured on the lower end of a plunger 44. The plunger 44 is so mounted in a screw 46 that it can be moved up and down in the screw, for a purpose hereinafter described. The plunger 44 is normally held in its raised position by a spring pressed plunger 47 mounted in the screw 46 and engaging a recess in the plunger 44. When the plunger 47 is withdrawn from the recess in the plunger 44 the latter and the pad 42 may be lowered towards the mold so that when a mold is being secured on the post 8 it may be accurately positioned in relation to the pad. The plunger 44 has secured on its upper end a collar 45 by which the plunger may be raised or lowered. The screw 46 is threaded through a beam 48 extending from left to right of the machine and secured at each end to the upper ends of a pair of bars 50, 50, see Figs. 1 and 2. The bars 50, 50 extend downwardly at each side of, and close to the sides of, the frame 70 and are pivotally connected at their lower ends

5 at 51 to a rearwardly extending substantially horizontal arm 52 which is pivoted at its rear end on a horizontal shaft 54 extending from right to left of the machine and secured in the frame 2 near the bottom thereof. The screw 46 has formed in its outer surface a groove 56 extending lengthwise of the screw and this groove is normally engaged by the end of a spring 10 pressed plunger 58, in the beam 48, which plunger prevents rotation of the screw. By disengaging the plunger 58 from the groove 56 and rotating the screw the presser pad 42 may be adjusted upwardly or downwardly and the pitch of the screw thread is such that a single rotation of the screw adjusts the presser pad upwardly or downwardly one eighth of an inch, so that the operator may be aware of the amount of vertical adjustment given to the pad by the number of revolutions given to the screw.

20 Pivoted on the pivot 51 which connects the lower ends of the bars 50, 50 to the forward end of the arm 52 is an upwardly and rearwardly extending double toggle link 60 (Figs. 1 and 2). The upper end of the toggle link 60 is pivotally connected, by a horizontal pivot 62 extending from left to right of the machine, to a second toggle link 64 which extends upwardly and forwardly and at its upper end is pivotally connected at 65 to the forward end of a rearwardly extending substantially horizontal lever 30 66. The lever 66 is pivoted, about mid-way between its ends, on a horizontal shaft 68 rotatably mounted in bearings on the machine frame and extending from left to right of the machine. The rear end of the lever 66 has pivotally connected to it the enlarged ends 68, 68 of two upwardly extending parallel short rods 10, 10, Figs. 2 and 3, which pass through openings, in which they are loosely guided, in a horizontal portion 72 of the machine frame. The short rods 40 10, 10 are screw threaded at their upper ends into the lower ends of two adjusting rods, one of which is shown at 74, which adjusting rods are coaxial with the short rods. Surrounding each adjusting rod is a strong spring 76 the lower end of which is supported by the said horizontal portion 72 of the machine frame. The upper end of each spring engages a washer 78 loosely mounted on the adjusting rod and between the said washer and a flange 80 formed on the adjusting rod 74 is a ball thrust bearing 82. By rotating the adjusting rods 74 and screwing them up or down on the short rods 10 the tension of the strong springs 76 may be adjusted. The enlarged ends 68 of the short rods 50 10 have on them leather washers 84 which are normally held up against the underside of the horizontal portion 72 of the machine frame by the springs 76. The upper end of each adjusting rod 74 has formed in it a keyway 85, and 60 passes through a worm gear 86 having in its bore a pin or key which enters the keyway in the upper end of the rod. Rotation of the worm gear 86, therefore, rotates the adjusting rod 74 but allows the rod to move up or down through 65 the gear. The worm gears 86 are supported against upward or downward movement in a bracket 88 secured to the upper face of the machine frame 2 near the rear thereof, which bracket supports the upper ends of the adjusting rods 74 and more or less shrouds the upper ends of the strong springs 76. The worm gears mesh with worms secured to a horizontal shaft 90 extending from left to right of the machine and rotatably mounted in bearings in 75

the said bracket 88 and the shaft has secured on it a hand lever 92 by which it may be rotated.

The pivot 62 which connects the two toggle links 60, 64 together has pivoted on it the forward end of a third link 94 which extends rearwardly and at its rear end is pivoted to a depending arm 96 of a bell-crank lever. The bell-crank lever is secured on the shaft 68 on which the lever 66 is pivoted and has a second rearwardly extending arm 98 to which the lower end of an upwardly extending connecting link 100 is coupled by a universal coupling. The upper end of the connecting link 100 embraces a crank 102 on the driving shaft 4 and the crank 102 and link 100 are universally connected to allow for the swinging movement of the bell-crank lever 96, 98.

As the driving shaft 4 rotates, the arm 96 of the bell-crank lever is swung forwardly by the crank 102 and connecting link 100 and the axis of the pivot 62 is moved to a position about three-eighths of an inch in front of the plane which passes through the axes of the pivots 51 and 65. During the straightening of the toggle the presser pad 42, which has been swung by the operator from a rearward, inoperative, position to a position over the heel lifts in the mold is moved down until it engages the uppermost lift; thereafter, during continued straightening of the toggle the lifts are compressed until their resistance to compression is such that the forward end of the lever 66 moves upwardly and its rear end moves downwardly against the action of the strong springs 76. In this way the presser pad 42 is, by power means, first moved down into engagement with the lifts in the mold and then the lifts are compressed, the pressure applied to the lifts being adjustable either by adjusting the heavy springs 76 or by adjusting the heightwise position of the presser pad 42 when it is in position over the lifts so that more or less of the straightening movement of the toggle is occupied in moving the presser pad down upon the lifts and correspondingly less or more of the said movement is occupied in compressing the strong springs. Preferably the presser pad 42 is adjusted in the beam 48, so that the pad, when it is swung forward by the operator, will clear always by about the same amount the top of the mold and the uppermost lift in the mold, the molds varying in height according to the height of the heel to be built. Thus the distance the presser pad has to move before it contacts with the uppermost lift in the mold is always substantially the same and the compression of the strong springs 76, and consequently the pressure applied to the lifts, is always substantially the same, but this pressure may readily be adjusted to suit the height of the heel or character of the material from which the lifts are formed by adjusting the springs 76.

While the toggle is in a substantially straightened condition, i. e. while the axis of the pivot 62 is moving to and fro across the plane passing through the pivots 51, 65 the nails are driven into the lifts. During the driving of the nails upward movement of the pad 42 is resisted by the springs 76 by which and the pad 42 a pressure of about a ton and a half is applied to the lifts.

When the presser pad 42 is swung forwardly over the lifts in the mold by the operator the bars 50 engage lugs 104, 104 extending laterally from the machine frame 2 which lugs 104

position the bars 50 and the presser pad 42 in their forward position, and when the bars 50 move downwardly during the straightening of the toggle 60, 64 blocks 106, 106 secured to the inner faces of the bars pass downwardly in grooves in the sides of the frame over the upper ends of which grooves the blocks 106 swing as the bars are moved forwardly. In this way the bars are guided during their downward and upward movement and any possibility of their swinging backward as they are moved down is prevented.

The bar 50 at the left of the machine has pivoted on it on a horizontal stud 108 extending from left to right of the machine a short arm 110, or tumbler 110, see Figs. 1 and 6, which is normally held by a spring 112 against a pin 114 in the bar 50 so that the tumbler 110 occupies an upwardly extending position parallel to the bar 50. The post 8 in which the nail driving mechanism is mounted has rotatably mounted in bearings at the rear of it a horizontal shaft 116 extending from left to right of the machine. The shaft 116 has rotatably mounted on it a lever 118 having one arm 120 which extends forwardly from the shaft 116 over the tumbler 110 when the presser pad 42 and bars 50 are swung forwardly. The lever 118 also has a second arm 122 which extends forwardly from the shaft 116 through an opening in the rear of the post 8 and just beneath the head 32, hereinbefore described, on the lower end of the stem 14 which projects downwardly from the nail block 10. When the presser pad 42 and bars 50 are swung forwardly the upper end of the tumbler 110 engages the under face of the arm 120 which projects over it and the tumbler 110 is swung backward against the action of its spring 112 (as shown in Fig. 6). When, during the operation of the machine, the bars 50 move downwardly the tumbler 110 is swung forwardly by its spring 112 against the pin 114 in the bar and, as the bars 50 rise after their downward movement, the upper end of the tumbler 110 engages the under face of the arm 120 and swings both the arms 120 and 122 of the lever 118 upwardly, raising the nail block 10 above the upper surface of the plate 38 on the post 8, lifting the nailed heel, about one quarter of an inch, in its mold. Thus power operated means is provided whereby a heel, which during the operation of the machine has been forced down into the mold and may have become stuck in the mold, is lifted and freed in the mold. To lift the nail block 10 and eject the nailed heel far enough to allow the operator to grasp the heel and lift it out of the mold, the arm 120, which projects over the tumbler 110, has extending laterally from it a pin 124, Figs. 1 and 6, arranged to be engaged by a hooked latch 126 when the arm 120 is raised as above described. The hooked latch 126 is pivoted on a forwardly and upwardly extending arm 128 on a bell crank lever 130 secured to the shaft 116 and holds the arm 120 and the nail block 10 in this raised position. The other arm 132 of the bell-crank lever 130 extends upwardly and rearwardly and has secured in it an eccentrically adjustable pin 134 positioned in the path of movement of the bar 50 at the left of the machine so that as that bar is swung back, and with it the tumbler 110, the bar engages the pin 134 and swings the bell-crank lever 130 rearwardly to raise, through the hooked latch 126 and lever 118, the nail block 10 and eject 75.

the heel into a position from which the heel may be readily removed from the mold. The bell-crank lever 130 is urged forwardly by a spring 136 secured to the bell-crank lever and to the post 8, and its movement in this direction is limited by an arm 138 secured on the shaft 116, which arm engages a pin 140 in the post, see Figs. 4 and 5. When the machine comes to rest the nail block 10 is held in its raised position by the latch 126 so that the operator can conveniently load the nail block with nails. After this is done, the latch 126 is released from the pin 140 by swinging the latch rearwardly on its pivot, against the action of a spring 142 which urges it forwardly, by means of a hand operated arm 144 on the latch so that the nail block 10 falls into its lowest position and a fresh supply of lifts for a new heel can be placed in the mold.

20 Provision is made for driving a single nail, if desired, into the lifts from the opposite end to that into which the heel building nails are driven as above described, i. e. from above.

The single nail driving means comprises a rod 146 screw threaded at its upper end into the plunger 44, so that the rod can be adjusted upwardly and downwardly and secured in adjusted position by a set screw 148 threaded transversely through the plunger 44. The threaded rod 146 has secured in its lower end a driver 150, the lower end of which is preferably slightly below the level of the bottom face of the presser pad 42. The lower end of the driver 150 passes through a sleeve 152 slidably mounted in the plunger 44 coaxial with the driver 150 and extending downwardly about three-quarters of an inch below the presser pad 42. The sleeve 152 has formed on it a shoulder 154 which is normally urged downwardly against a shoulder formed in the bore in the plunger 44 by a compression spring 156, which engages the upper end of the sleeve 152 and a shoulder on the threaded rod 146. The sleeve 152 near its lower end has formed in it an opening extending from the outer face of the sleeve into the bore in the sleeve. Projecting through this opening into the bore in the sleeve is a spring 158 secured to the sleeve. This spring 158 is so shaped that it engages and holds in the bore of the sleeve a nail pushed upwardly head first into the bore by the operator. When the presser pad 42 is swung over the lifts the sleeve 152 is so adjusted that the lower end of the sleeve is preferably about one-quarter of an inch above the lifts and as the presser pad 42 is moved down into engagement with the uppermost lift in the mold the lower end of the sleeve engages the uppermost lift and the sleeve is held stationary, or substantially so, thereby during the continued descent of the presser pad. During continued descent of the pad the driver 150 pushes the nail into the lifts, the pad 42 moving down over the sleeve 152 and the spring 156 above the sleeve being compressed.

65 The clutch through which the driving of the machine is effected is controlled by a hand lever 160 pivoted on a stud 162 secured in the right-hand side of the machine frame 2. The hand lever 160 has three arms, one of which extends upwardly and forwardly from the pivot 162 and has at its outer end a hand-piece by which it may be swung downwardly. Another arm 164 of the hand lever extends rearwardly and is connected by a link 166 and lever 168 to the tripping mechanism of the clutch, which

is enclosed in the casing 180. When the lever 160 is depressed by the operator, the clutch is permitted to engage and the driving shaft 4 makes a single revolution.

5 The third arm 200 of the lever 160 extends substantially horizontally forwardly and has on its under side an arcuate face 202 substantially radial to the pivot 51 of the bars 50, 50 when the beam 48 is in its raised position. The bar 50 at the right-hand side of the machine has 10 extending laterally from it a pin 204 which, when the presser pad 42 is swung back from over the mold 40, is just beneath the arcuate face 202 of the arm 200 and prevents the hand lever 160 from being actuated until the presser pad 42 has been swung over the mold, the arcuate face 202 on the arm 200 being of such a length that the pin 204 in the bar 50 is just in front of the forward end of the arm 200 when the presser pad 42 is in its fully forward 20 position so that only when the bars 50 are in their fully forward position can the hand lever 160 be actuated. The arm 200 has slidably mounted in it a rod 206 (Figs. 7 and 8) which can be moved lengthwise of the arm so that it extends 25 over the top of the pin 204 in the bar 50 when the presser pad has been moved forward over the mold 40 and prevents actuation of the hand lever 160 to start the machine. This may be done when, for instance, the operator is changing molds and in so doing moves the pad 42 over the mold and moves it down, as hereinbefore described, to enable him to position the mold accurately beneath the pad. The rod 206 has extending from it a stud 208 which projects 30 through a slot 210 in the arm 209. The stud 208 has slidably mounted on it a sleeve 212 the reduced end of which is held in a recess in the arm 200 by a spring 214 when the rod is withdrawn from over the pin 204. When the 40 sleeve is pulled outwardly against the action of the spring 214 and the reduced end of the sleeve thereby withdrawn from the recess in the arm 200 the rod 206 may by means of the sleeve be moved outwardly of the arm 200 and held there 45 by the engagement of the end of the sleeve with the arm.

The face 202 on the arm 200 and the rod 206, therefore, provide means to prevent the machine from being accidentally started at any 50 time.

The machine is provided with a guard 216 which moves down in front of the presser pad and mold as the presser pad is moved forwardly over the mold and prevents the operator or other person from having his hand caught between the presser pad and mold when the presser pad is moved down. The guard 216 is pivotally connected to two pairs of substantially parallel arms 218, 220, one pair of arms being pivoted on a 55 bracket 221 secured to one of the bars 50 and the other pair being pivoted on a bracket secured to the other bar. The pivots and arms 218, 220 form a parallel link mechanism. The lower arm 220 at the right of the machine has 60 extending downwardly from its hub an arm 222, thereby forming a bell-crank lever. The downwardly extending arm 222 has connected to it one end of a tension spring 224 which extends forwardly and at its other end is connected to the bar 50 at that side of the machine so that the spring tends to move the guard 216 upwardly and, because of the parallel link mechanism, the guard is moved upwardly substantially parallel to the bars 50. The depend- 70 75

ing arm 222 of the bell crank lever has in its outer end a laterally extending pin 226 which enters a slot 228 extending along a rearwardly extending link 230 the rear end of which is pivoted on the bracket 88. When the bars 50 and presser pad 42 are in their forward and fully raised position the guard is down and in front of the presser pad and mold and retains substantially this position as it moves down and up again with the bars 50. The pin 226 in the depending arm 222 of the bell crank lever is at this time in engagement with the forward end of the slot 228 in the link 230 and the link 230 is holding the guard down against the action of its spring 224. When the bars 50 are swung rearwardly the pin 226 remains for a time in engagement with the forward end of the slot 228 in the link and the spring 224 moves the guard 216 upwardly as the bars swing back until the upper arms 218 engage the under side of the beam 48 after which the pin 226 moves rearwardly in the slot 228 in the link 230. When the bars 50 and presser pad 42 are moved forwardly the guard 216 remains up until the pin 226 engages the forward end of the slot 228 in the link 230 after which during the continued forward movement of the bars and presser pad the guard is moved down.

To enable the operator, when loading nails into the nail block 10, to see whether nails have been placed in all or the desired number of holes in the block means is provided whereby the nail drivers 18 may be raised so the points of the nails in the block may be raised a little above the plate 28 and the operator can see which nail holes have been filled with nails. For this purpose a lever 232 is pivoted on the shaft 116. The lever 232 has extending from it an arm 234 which extends underneath a portion 236 (Fig. 5) of the plunger 24. The lever 232 also has an arm 238 by which the arm 234 may be swung upwardly to raise the plunger 24 and drivers 18.

Having described the invention, what is claimed as new and desired to be secured by Letters Patent is:

1. In a heel building machine, the combination of a heel mold, a movable nail block constituting the bottom of the mold, means for lifting the nail block a short distance to free a heel from the mold, and additional means for lifting the nail block further in the mold to eject the heel.

2. In a heel building machine, the combination of a heel mold, a movable presser pad support carrying a presser pad movable toward and away from the mold, a movable nail block constituting the bottom of the mold, and means controlled by movement of said support away from the mold for lifting the nail block in the mold to free a heel therefrom.

3. In a heel building machine, the combination, of a heel mold, a presser pad movable successively vertically and horizontally away from the mold, a movable nail block constituting the bottom of the mold, and means for lifting the nail block in the mold in successive steps during the vertical and horizontal movements, respectively, of the presser pad.

4. In a heel building machine, the combination of a heel mold, a presser pad mounted for movement toward or away from the mold in two different directions, a movable nail block con-

stituting the bottom of the mold, means for lifting the nail block a short distance to free a heel in the mold during movement of the presser pad in one direction away from the mold, and means for lifting the nail block further in the mold to eject a heel during movement of the presser pad in the other direction away from the mold.

5. In a heel building machine, the combination of a heel mold, a presser pad movable toward and away from the mold, a movable nail block constituting the bottom of the mold, means for lifting the nail block in the mold during movement of the presser pad away from the mold and maintaining it in convenient nail receiving position, and additional means for dropping the nail block to the bottom of the mold after the nails have been inserted in it.

6. In a heel building machine, the combination of a heel mold, a movable nail block constituting the bottom of the mold, power operated means for lifting the nail block in the mold to eject a heel and present the block in convenient position to receive nails, and manually operable means for dropping the nail block to the bottom of the mold after the nails have been inserted in it.

7. In a heel machine, the combination of a nail block, nail drivers reciprocal through the nail block, power means for operating the drivers, and additional means for advancing the drivers at the will of the operator, independently of said power means, to permit inspection of the nails with which the block is loaded.

8. In a heel machine, the combination of a nail block, nail drivers reciprocal through the nail block, power means for operating the drivers, and manual means for advancing the drivers independently of said power means, to permit inspection of the nails with which the block is loaded.

9. In a heel building machine, the combination of a heel mold, a presser pad movable into and out of register with the mold and movable toward the mold when it is in register there- with, power mechanism for moving the pad toward the mold, means for preventing application of power to the pad when it is not in register with the mold, and additional means for preventing application of power to the pad when it is in register with the mold.

10. In a heel building machine, the combination of a heel mold, a presser pad movable into and out of register with the mold and movable toward the mold when it is in register there- with, power mechanism for moving the pad toward the mold, means for permanently preventing application of power to the pad when it is not in register with the mold, and additional means, operable at will, for preventing application of power to the pad when it is in register with the mold.

11. In a heel building machine, the combination of a heel mold, a presser pad movable toward and away from the mold, power means for so moving the pad, and manually controllable means permitting the pad to be moved into the mold independently of said power means, to facilitate positioning of the mold.
